UNITED STATES PATENT OFFICE.

ISAAC P. WENDELL, OF PHILADELPHIA, PENNSYLVANIA.

CAR-AXLE BOX.

SPECIFICATION forming part of Letters Patent No. 268,579, dated December 5, 1882.

Application filed April 3, 1882. (No model.)

To all whom it may concern:

Be it known that I, ISAAC P. WENDELL, a citizen of the United States, residing at Philadelphia, in the county of Philadelphia and State of Pennsylvania, have invented certain new and useful Improvements in Dust-Shields for Car-Axle Boxes, of which the following is a specification, reference being had therein to the accompanying drawings, wherein—

10 Figure 1 is an elevation of a dust-shield embodying my invention, the car-axle being shown in section. Fig. 2 is a vertical longitudinal section of the same. Fig. 3 is a detail end elevation, partly in section. Fig. 4 is a detail side elevation; and Fig. 5 is a broken section of car-axle and box with my improved shield applied thereto, the latter being shown in elevation.

15 My invention has relation to dust-shields for car-axle boxes, and has for its object to provide a shield which will effectually exclude dust from the axle-box and prevent the oil in the latter leaking out thereof, such shield being so constructed that its wear is automatically taken up, thereby maintaining a tight joint between such shield and the car-axle.

20 My invention accordingly consists of the novel combination, construction, and arrangement of parts, as hereinafter specifically described and claimed.

25 Referring to the accompanying drawings, A represents a car-axle; B, the box, provided with recessed rear wall, as shown at b, Fig. 5, for the reception of dust-shield C. The latter is composed of two semicircular or other appropriately configured sections, D D, formed with lugs d d, which overlap each other when said sections align with each other, as shown at d'. The sections D are hollow or formed with recesses D', in which is placed a packing of asbestos or other similar or suitable material, D².

30 E represents a metallic band passing around sections D to hold the latter in position. The ends e e of said band are threaded and pass through unthreaded openings f f in cap or cover F, and are provided with springs G and locking-nuts g g' or other suitable fastening appliances. The tendency of the springs G is to hold the band E in close impingement with the sections D, and as the latter wear away the resilient action of the springs G causes the lower part of said band to approach the axle A, thereby au-

tomatically moving the sections together to take up such wear and duly maintain the joint between the sections and the axle.

H H represent plate-springs, riveted, as shown, to one of the sections D; or, if desired, both of said sections may be provided with such springs. The latter cause the shield C to bear against the wall b' of recess b, as plainly shown in Fig. 5, to make a tight joint therewith, and thereby increase the effectiveness of the shield.

The lower side, f', of cover F is shaped to conform to the outline of the adjacent section D, as shown.

I have described the packing D² as being composed of asbestos, and such I prefer to use for the reason that it is incombustible. Hence, if at any time the waste in the axle-box should take fire, such packing will not be burned or destroyed; but I do not limit myself to the use of such material, as any other suitable form of packing may be placed within the sections D D.

If desired, a layer of asbestos, D³, may be interposed between the wall b' and the sections D of the shield. Such asbestos, yielding to the inequalities of the metal wall b', more readily and effectually forms a tight joint between said wall and sections. The layer of asbestos D³ may be cemented or otherwise secured to sections D, as desired.

I claim as my invention—

1. A dust-shield for car-axle boxes, composed of two hollow metal sections, in each of which is placed a flexible or absorbent packing, the curved edges of which are flush with or project beyond the curved edges of said sections, a surrounding band, and springs, with retaining nuts or pins secured to each end of said band for causing it to automatically take up the wear of said sections, substantially as shown and described.

2. The combination of cap or cover F, hollow or recessed sections D, having packing D², spring or springs H, band E, and springs G, with locking-nuts g g', substantially as shown and described.

3. The recessed or hollow sections D, lugged at d, and provided with packing D², and spring or springs H, substantially as shown and described.

4. The recessed or hollow sections D, pro-

vided with a packing of asbestos material, substantially as shown and described.

5. The recessed or hollow sections D, provided with a packing, D², and springs H, substantially as shown and described.

6. The combination of sections D D, provided with packing D², cap F, band E, provided with springs G and nuts g g', and the

springs H, substantially as shown and described.

In testimony whereof I affix my signature in presence of two witnesses.

ISAAC P. WENDELL.
